CLAIM

The ornamental design for a lighting fixture, as shown and described.

DESCRIPTION

FIG. 1 is an isometric view of a lighting fixture. FIG. 2 is an enlarged view of a portion of the lighting fixture as shown in FIG. 1. FIG. 3 is a bottom view of the lighting fixture of FIG. 1. FIG. 4 is an enlarged view of a portion of the lighting fixture as shown in FIG. 3. FIG. 5 is a side view of the lighting fixture of FIG. 1. FIG. 6 is an enlarged view of a portion of the lighting fixture as shown in FIG. 5. FIG. 7 is another side view of the lighting fixture of FIG. 1. FIG. 8 is another side view of the lighting fixture of FIG. 1. FIG. 9 is another side view of the lighting fixture of FIG. 1. FIG. 10 is a top view of the lighting fixture of FIG. 1. FIG. 11 is a cross-section view of the lighting fixture along the line 11-11 in FIG. 3; and, FIG. 12 is an enlarged view of a portion of the cross section of the lighting fixture as shown in FIG. 11. The broken lines in the drawings denote structure that is not part of the claimed design.
